United States Patent Office

Des. 232,224

Patented July 30, 1974

232,224

TIMER OR SIMILAR DEVICE

Richard W. Dobyns, 1351 Graymill Drive,
Scotch Plains, N.J. 07076

Filed July 9, 1973, Ser. No. 377,424

Term of patent 14 years

Int. Cl. D10—03

U.S. Cl. D10—40

FIG. 2

FIG. 1

FIG. 4

FIG. 3

FIG. 6

FIG. 5

FIG. 1 is a front perspective view of a timer or similar device, showing my new design;

FIG. 2 is a left side view thereof;

FIG. 3 is a top view thereof;

FIG. 4 is a front view thereof;

FIG. 5 is a rear view thereof;

FIG. 6 is a bottom view thereof.

The toothbrush shown is a handle for starting the timer.

I claim:

The ornamental design for a timer or similar device, substantially as shown and described.
